UNITED STATES PATENT OFFICE.

FRANZ MÄDLER, OF BERLIN, GERMANY, ASSIGNOR TO MAEDLER ENGINE CORPORATION, OF CLEVELAND, OHIO, A CORPORATION OF MARYLAND.

INTERNAL-COMBUSTION ENGINE.

Original application filed July 16, 1920, Serial No. 396,870. Divided and this application filed November 25, 1924. Serial No. 752,185.

(GRANTED UNDER THE PROVISIONS OF THE ACT OF MARCH 3, 1921, 41 STAT. L., 1313.)

To all whom it may concern:

Be it known that I, FRANZ MÄDLER, a citizen of Germany, residing at 21 Emserstrasse, Berlin W., Germany, have invented 5 certain new and useful Improvements in Internal-Combustion Engines (for which I have filed applications as follows: Germany, Sept. 26, 1918; Germany, May 20, 1919; Germany, June 20, 1919; Germany, 10 Oct. 24, 1919; Germany, Oct. 24, 1919; Germany, Apr. 17, 1920; Germany, April 17, 1920; Germany, Jan. 31, 1921; Germany, 15 Jan. 31, 1921; England, June 15, 1920; England, June 18, 1920; England, June 18, 1920; England, July 5, 1920; Austria, June 8, 1920; Switzerland, June 12, 1920; Denmark, June 19, 1920; Czechoslovakia, June 21, 1920; Sweden, June 25, 1920; Poland, June 28, 1920; Finland, June 30, 1920; Italy, 20 June 30, 1920; Norway, June 30, 1920; Belgium, July 2, 1920; Holland, July 5, 1920; Spain, July 8, 1920; Hungary, July 9, 1920; Canada, July 10, 1920; France, July 10, 1920; Portugal, July 10, 1920; Australia, 25 Aug. 23, 1920), of which the following is a specification.

My invention is for a new and improved internal combustion engine particularly adapted for heavy fuels containing non-volatile matter. This invention finds special application in two-cycle engines, although not limited thereto.

In my new engine I utilize the high pressure and temperature of a very small proportion of the combustion gases in the working cylinder to vaporize a fuel charge in an auxiliary chamber. The vaporized fuel is held in the closed chamber under high pressure until released at the proper moment for injection into the air charge of the main cylinder. Particles of non-volatile matter in the fuel adhere to the walls of the chamber or may otherwise be trapped therein.

In order to explain the principles of my invention, I have diagrammatically illustrated a two-cycle engine in the accompanying drawings. For the sake of clearness and simplicity, I have shown only such parts of an engine as are necessary in a detailed description of my invention, it being evident that all such other mechanical de-

tails as go to make up a complete engine are within the skill of the engineer.

In the drawings which form part of this specification,

Fig. 1 illustrates, more or less diagrammatically, a longitudinal cross-section of a two-cycle engine embodying my invention, the position of the main piston being just after the moment of firing;

Fig. 2 is a view similar to Fig. 1, the position of the parts being approximately at the moment when the fuel charge is injected into the air charge in the main cylinder.

The main cylinder 1 has a reciprocable working piston 2, which is connected to the crank-shaft in the usual way. Air is admitted into the cylinder through a valve 3 of any practical construction and actuated through suitable mechanical means from the cam-shaft. The operation and timing of valve 3 will be understood by those skilled in the art. The exhaust gases escape from the main cylinder through one or more exhaust ports 4, connected to the open air through an exhaust pipe.

A small auxiliary chamber 5, of correct design, size and shape, is attached to or otherwise operatively connected with the main cylinder for the reception of a very small portion of combustion gases from the interior of the main cylinder during the firing stroke. In practical experience it has been found that the volume of the auxiliary chamber will only be a small fractional portion of the working volume of the main cylinder, depending in each instance upon such factors as the type and amount of fuel used, compression ratio of the engine, and the pressure and temperature of the explosion. In the drawings, I have shown the chamber 5 screwed onto a projection 6 extending from the head of the cylinder, but any other suitable support for the chamber may be employed. The chamber 5 has an opening at the top closed by a removable screw-plug 5' for access to the chamber when desired.

The auxiliary chamber 5 communicates with the main cylinder through channels or passages 7 and 8, which are controlled by a valve 9. I would have it understood that valve 9 represents any practical form of

valve for controlling the connections between the auxiliary chamber 5 and the main cylinder 1. Valve 9 may be operated and timed by any suitable means. In the drawings I have shown, by way of illustration, a spring 10 which normally tends to open the valve 9. A second spring 10' is used to close the valve 9 when compressed to a greater strength than spring 10 by cam-shaft 12 through roller 15 operating the valve tappet 15'. The cam-shaft 12, suitably driven from the crank-shaft, has cams 13 and 14 properly arranged thereon. As long as the roller 15 runs on the neutral portion of cam-shaft 12, the valve 9 is held closed by the compressed spring 10', as shown in Fig. 1. Either depression 13 or 14 allows the valve to open by releasing the pressure on spring 10' so that spring 10 will 20 open the valve, as illustrated in Fig. 2.

Fuel is admitted into channel 7 through an inlet 17, adapted to be connected to a suitable source of fuel supply. A proper quantity of fuel is admitted through inlet 25 17 and is deposited approximately at the point 18 in passage 7. It will be understood that fuel inlet 17 is provided with a suitable check valve to close this passage when the combustion gases carry the deposited 30 fuel into auxiliary chamber 5, as will presently be explained.

The operation of my invention is as follows:

Let us suppose that a metered amount of 35 fuel has been pumped through fuel inlet 17 and deposited in the space 18 of channel 7 during the compression stroke of the main piston. The valve 9 is closed during the compression stroke, and is opened at a time 40 when the combustion gases in the working cylinder have reached the desired pressure and temperature, so that a very small portion of these gases enters the chamber 5 through the connecting channels 8 and 7. 45 This portion of the gases rushing into the chamber 5 carries the deposited fuel in space 18 along. Owing to the pressure, temperature and velocity of the combustion gases as they rush into chamber 5, the fuel is immediately vaporized, and any particles 50 contained in the fuel which are not volatile and so cannot be vaporized, are blown against the walls of chamber 5 where they adhere. The cylinder has been charged 55 with fresh air at approximately atmospheric pressure, and the air admission valve 13 and exhaust port 4 are closed. Then the valve 9 is again opened, so that the prepared gaseous fuel rushes out under its own high pressure into the air charge in the main cylinder. The temperature and pressure at which 60 the combustion gases enter the auxiliary chamber 5 depend upon the timing of valve 9. This valve may be opened at a moment 65 when the combustion gases in the working

cylinder have reached approximately their highest temperature and pressure, or at any other desired moment.

This method is particularly suitable for heavy oils containing large amounts of non-volatile residual matter, because any particles of the fuel which cannot be vaporized impinge on the walls of the chamber 5, where they adhere and may later be removed. In this way, solid particles contained in the fuel are prevented from entering the working cylinder.

The fuel, instead of being stored in channel 7, may be injected directly into chamber 5. This injecting is done through any suitable opening and by any suitable means.

The factors which enter into consideration in determining the volume and design of chamber 5 also to some extent govern the timing of valve 9 for the admission of the combustion gases from the working cylinder into the auxiliary chamber.

To start the engine, an easily vaporized fuel is used. After the ignition of this easily gasified fuel and air mixture has taken place, the hot high-pressure combustion gases take up the preparation of the normal fuel, as previously described. However, by keeping the chamber 5 at a sufficient temperature, it is possible 95 to start on the fuel that the engine normally uses.

For the sake of simplicity, I have shown only a single cylinder in the drawings, but it is obvious that my invention is applicable to internal combustion engines having a plurality of working cylinders. Also, each working cylinder may have more than one auxiliary chamber, so that when one chamber is disconnected for cleaning or repair, another chamber may be put into operation without interfering with the running of the engine.

Although I have herein shown and described a specific construction, I want it 110 understood that I have done so merely to explain my invention. The engine shown in the drawings is to be regarded as illustrative of my invention, and not by way of limitation or restriction. It is obvious that the 115 underlying features of my invention may be mechanically embodied in various forms of engines without departing from the scope of the invention as defined in the appended claims.

I make no method claims in this application, for the method herein set forth forms the subject matter of my co-pending application Serial Number 396,870, filed July 16, 1920, of which this apparatus case is a continuation or division.

I claim as my invention:

1. In an internal combustion engine, a working cylinder, a small auxiliary chamber arranged to communicate with the in-

- terior of said cylinder, normally closed valve mechanism for controlling said communication, means for momentarily operating said valve mechanism to admit combustion gases under high temperature and pressure from the main cylinder into the auxiliary chamber, means for depositing a charge of fuel in the path of said gases whereby said gases vaporize the fuel in said chamber, said chamber being held positively closed by said valve mechanism after the combustion gases and fuel are admitted therein, so that said combustion gases and vaporized fuel are retained in said chamber under high temperature and pressure, means for admitting an air charge into the main cylinder, and means for operatively operating said valve mechanism to momentarily open communication between the auxiliary chamber and the main cylinder for injecting the vaporized fuel from the auxiliary chamber into the air charge in the main cylinder.
2. In an internal combustion engine, a working cylinder, a small auxiliary chamber arranged to communicate with the interior of said cylinder, normally closed valve mechanism for controlling said communication, means for momentarily operating said valve mechanism approximately at a time when the combustion gases in the main cylinder reach the desired temperature and pressure, so that a very small proportion of these combustion gases enters the auxiliary chamber through said communication, means for depositing a charge of fuel in the path of said gases, whereby said gases vaporize the fuel in said chamber, said chamber being held positively closed by said valve mechanism after the combustion gases and fuel are admitted therein, so that said combustion gases and vaporized fuel are retained in said chamber under high temperature and pressure, means for filling the main cylinder with a predetermined volume of air charge at a pressure below that in the auxiliary chamber, and means for positively operating said valve mechanism to momentarily open communication between the auxiliary chamber and the main cylinder for injecting the vaporized fuel from the auxiliary chamber into the air charge in the main cylinder.
3. In an internal combustion engine, a main cylinder provided with a working piston, an auxiliary chamber communicating with said cylinder and arranged to receive combustion gases from the main cylinder under high temperature and pressure, means for subjecting a fuel charge to the action of said gases which vaporize the volatile particles of the fuel in said chamber, means for filling the main cylinder with an air charge, positively acting valve mechanism for retaining the vaporized fuel and combustion gases in said chamber under high temperature and pressure, and means for mechanically operating said valve mechanism at the proper moment to inject said vaporized fuel into the air charge in the main cylinder, 70 non-volatile solid particles of the fuel adhering to the walls of said chamber.
4. In an internal combustion engine operating on fuel oil, means for preparing a fuel charge for efficient mixing and combustion with an air charge in the working cylinder of the engine, said means comprising a small auxiliary chamber constructed and arranged to receive combustion gases from the main cylinder under high temperature 80 and pressure, a single passage through which said chamber communicates with a source of fuel supply, means for supplying a fuel charge through said passage into the path of said gases, whereby said gases vaporize 85 the fuel in said chamber, and positively controlled means for retaining the vaporized fuel in said chamber under high pressure preparatory to injection into the air charge in the working cylinder. 90
5. In an internal combustion engine, a working cylinder provided with an auxiliary chamber arranged to communicate therewith, a single passage through which said chamber communicates with a source of fuel 95 supply, means for supplying a fuel charge through said passage and depositing the same in a predetermined position, controllable mechanism for admitting combustion gases from the working cylinder into said 100 chamber at a moment when approximately the required pressure and temperature exist in the working cylinder, said fuel charge being so deposited that it is carried by said combustion gases into the auxiliary chamber and vaporized, said mechanism positively closing off the auxiliary chamber from the main cylinder and the source of fuel supply to retain the vaporized fuel in said chamber under high temperature and 105 pressure, means for filling the working cylinder with an air charge, and means for positively actuating said mechanism to release said combustion gases and vaporized fuel in the auxiliary chamber, whereby said 110 combustion gases inject the vaporized fuel into the air charge in the working cylinder. 115
6. As a means for separating non-volatile solid particles from the fuel charges of internal combustion engines operating on fuel 120 oil, a small auxiliary chamber constructed and arranged to be filled with combustion gases from the working cylinder under high temperature and pressure, means for subjecting a fuel charge to the action of such 125 gases which vaporize the volatile portions of the fuel in said chamber, and means for positively retaining said combustion gases and vaporized fuel under high pressure and temperature in said chamber and subse- 130

quently releasing said gases and vaporized portions of the fuel for injection into an air charge in the working cylinder, the non-volatile solid particles of fuel adhering to the walls of said chamber and being thus positively prevented from entering the working cylinder or returning to the source of fuel supply.

7. In an internal combustion engine operating on fuel oil, a main cylinder provided with a working piston, an auxiliary chamber arranged to communicate with said cylinder, a single passage through which said chamber communicates with a source of fuel supply, controllable mechanism for admitting combustion gases from the working cylinder into said chamber at a moment when approximately the required pressure and temperature exists in the working cylinder, means independent of the action of

said gases for supplying a fuel charge into the path of said gases, whereby said gases vaporize the supplied fuel charge in said chamber, said mechanism positively closing off the auxiliary chamber from the main cylinder and the source of fuel supply to retain the vaporized fuel in said chamber under high pressure and temperature, means for filling the working cylinder with an air charge, and means for positively actuating said mechanism to release said combustion gases and vaporized fuel in the auxiliary chamber, whereby said combustion gases inject the vaporized fuel into the air charge in the working cylinder, the non-volatile particles of fuel being retained in said chamber.

In testimony whereof, I affix my signature this 24th day of October, 1924.

FRANZ MÄDLER.
